UNITED STATES PATENT OFFICE.

WILLIAM JOHNSON, OF MOTT, CALIFORNIA.

SUPPORT FOR WINDOW-AWNING.

SPECIFICATION forming part of Letters Patent No. 592,786, dated November 2, 1897.

Application filed May 11, 1897. Serial No. 636,051. (No model.)

To all whom it may concern:

Be it known that I, WILLIAM JOHNSON, a citizen of the United States, residing at Mott, in the county of Siskiyou and State of California, have invented certain new and useful Improvements in Supports for Window-Awnings, of which the following is a full and complete specification, such as will enable those skilled in the art to which it appertains to make and use the same.

This invention relates to window-awnings, and particularly to supports therefor; and the object of the invention is to provide an improved support for window-awnings and an improved shade or cover for the awning when not in use.

The invention is fully disclosed in the following specification, of which the accompanying drawings form a part, in which the separate parts of my improvement are designated by the same numerals of reference in each of the views, and in which—

Figure 1 is a front view of a window provided with my improved awning-support, the awning being removed and a part of the construction being shown in section; Fig. 2, a sectional side view of the awning in position; Fig. 3, a front view of a detail of the construction on an enlarged scale, and Fig. 4 a side view thereof.

In the drawings forming part of this specification I have shown an ordinary window-frame, consisting of the sides 5, the top 6, and the bottom 7, and in the practice of my invention I provide a window-awning 8, which is connected with an ordinary spring-roller 9, and the spring-roller 9 is mounted in a casing or shield 10.

The casing or shield 10 is circular in form and closed at both ends and open at the lower side, and the spring-roller 9 is pivotally supported at the end of said casing, as shown at 11, or said roller may be supported by the frame of the window.

The back of the casing or shield 10 is provided with slots 12, which are designed to receive headed pins, nails, or screws 13, which are secured in the top of the window-frame, and by means of this construction the casing or shield 10 is held in place and may be removed from the window-frame or connected therewith whenever desired.

The awning 8 is preferably provided with side pieces 14 in the usual manner, and these side pieces when the awning is in use are connected with the sides of the window-frame by hooks or other fastening devices, as shown at 15.

The lower end of the main portion of the awning is provided with a cross-rod at 17, and 60 pivotally connected with each end thereof are arms 18, which are pivotally connected with the sides of the window, as shown at 19. This connection of the arms 18 with the sides of the window-frame is made by means of 65 plates 20, which are secured to the said sides of the frame, and said plates are provided with pivot-pins 21 and with circular disks or plates 22, on the outer side of each of which is formed a circular or segmental shoulder or 70 projection 23, and mounted on or connected with each of the pivot-pins 21 is a curved spring 24, one end of which bears upon the lower end of the corresponding circular or segmental shoulder or projection 23, and the 75 other end of each of said springs operates beneath a pin 25, secured to the adjacent arm 18. The object of this construction is to throw the arms 18 upwardly into the position shown in Fig. 1 when the window-awning is 80 raised, and pivotally connected with the outer ends of the arms 18 are brace-rods 26, which are adapted to be connected with headed pins or similar devices 27, secured to the sides 5 of the window-frame.

The braces 26 are provided on their under sides and near their free ends with transverse notches or recesses 28, which are adapted to receive the pins 27, and the object of said rods is to hold the lower end of the awning in the position shown in Fig. 2 when said awning is in use.

The operation will be readily understood from the foregoing description when taken in connection with the accompanying drawings and the following statement thereof.

When the awning is not in use, the rods 26 are disconnected from the pins 27, and the spring-roller 19 will operate to raise the awning, said awning being rolled on said spring-roller, as will be readily understood; but, in order that the roller 9 may operate, the side pieces 14 of the awning are first disconnected from the sides of the frame of the window and

folded inwardly adjacent to the inner side of the main part of the awning, and when the awning is raised the arms 18 and the rods 26 will assume the position shown in Fig. 1.

5 The awning may be disconnected from the arms 18 and drawn upwardly, so as to be entirely concealed within the shield or casing 10, and said shield or casing 10 will serve as a protector for the awning and protect the same 10 from the elements when not in use, or the arms 18 may be made long enough to reach from their pivotal points at 19 to the upper portion of the window-frame, if desired.

15 My improvement is simple in construction and operation and is perfectly adapted to accomplish the result for which it is intended.

Having fully described my invention, I claim as new and desire to secure by Letters Patent—

20 1. An awning attachment for windows, consisting of a shield or casing which is adapted to be secured to the frame of the window at the top thereof, said shield or casing being open at its lower side, and being provided with

25 a spring-roller which is mounted therein, an awning connected with said spring-roller, and devices connected with the lower end of said awning for holding the same in position when in use, said devices consisting of spring-operated arms which are connected with the

30 lower end of the awning, and with the sides of the window-frame, and brace-rods connect-

ed with the outer ends of said arms and adapted to be connected with pins or projections secured to the side of the window-frame, substantially as shown and described. 35

2. An awning attachment for windows consisting of a shield or casing which is adapted to be secured to the frame of the window at the top thereof, said shield or casing being open at its lower side, and being provided with a spring-roller which is mounted therein, an awning connected with said spring-roller, and devices connected with the lower end of said awning for holding the same in position when 40 in use, said devices consisting of spring-operated arms which are connected with the lower end of the awning, and with the sides of the window-frame, and brace-rods connected with the outer ends of said arms and adapted to be connected with pins or projections secured to the side of the window-frame, said awning being also provided with side pieces which are adapted to be detachably connected with the sides of the window-frame, substantially as shown and described. 50

In testimony that I claim the foregoing as my invention I have signed my name, in presence of the subscribing witnesses, this 1st day of May, 1897.

WILLIAM JOHNSON.
